SAFETY SWITCH

Herman J. Hammerly, Plainville, Conn., assignor
to The Trumbull Electric Manufacturing Company, Plainville, Conn., a corporation of Connecticut

Application September 25, 1946, Serial No. 699,150

8 Claims. (Cl. 200—155)

1

My invention relates to electric switches of the enclosed or safety type in which the switching mechanism is mounted in a box and provided with an actuating member outside of the box.

The main object is to provide a simple and compact and yet efficient switch of the low price field.

With that in mind, I have provided a box with a hinged cover in which is mounted an insulating base which carries the circuit terminals, the protective devices, the switch contacts and the contact making and breaking rotor. The outer end of the actuating member carried by the insulating base projects through the cover and is provided with means for sealing the joint between the cover and the actuator and for locking the switch.

The proposed form of the invention is shown in the accompanying drawings and will be described in the following specification.

Fig. 1 is a front view of an enclosed switch embodying one form of my invention and indicating in dotted lines the outline of the interior switch base.

Fig. 2 is an end view of the switch box and showing the actuating handle member.

Fig. 3 is a front view of a fragment of the cover and showing the actuating handle member on a larger scale.

Fig. 4 is a cross-sectional view of the actuating handle shaft taken on the plane of the line 4—4 of Fig. 5.

Fig. 5 is a vertical sectional view and elevation showing the shaft and a fragment of the supporting parts.

Fig. 6 is a plan view of the base with attached parts on a scale larger than that of Fig. 1.

Fig. 7 is a vertical sectional view on the plane of the line 7—7 of Fig. 6 and showing the switch rotor in the closed circuit position.

Fig. 8 is a sectional view of a fragment of the base on the plane of the line 8—8 of Fig. 6 and showing the relation of a load circuit terminal and the connected fuse terminals and switch contact.

Fig. 9 is a sectional view of a fragment of the base on the plane of the line 9—9 of Fig. 6 and showing the relation of a line circuit terminal and a switch contact and fuse terminal.

Fig. 10 is a bottom plan view of the base with the attached line terminals and the switch rotor in the closed circuit position.

Fig. 11 is a plan view of the rotor with its contacts.

Fig. 12 is a sectional view of the rotor on the plane of the line 12—12 of Fig. 11.

2

Fig. 13 is a bottom plan view of the rotor with its contacts.

Fig. 14 is a plan view showing a modification of the switch base and parts for cartridge type fuse protection.

The box body 15 may be of any suitable form and provided with a cover 16 which is preferably hinged at 17.

The switching mechanism mounted within the box is all carried by an insulating base 18 which is adapted to be secured to the bottom of the box in any suitable manner as for instance by a screw (not shown) through the passage 19 in the base.

Line terminals 20, 20 are secured to opposite corners of the base at the upper edge and load terminals 21, 21 are secured to the base at opposite corners of the lower edge of the base. Each line terminal has a spring contact arm extension 22 at the rear held in place for instance by a screw or stud 23. The form of device shown in Figs. 6 and 7 is intended to carry protective devices in the form of fuse plugs (not shown) and for this purpose a screw-threaded fuse socket 24 is mounted on each side of the base and secured to an extension 25 of the load terminal by means of screws or studs 26. The center contact 27 for each fuse plug is preferably in the form of a serrated stud forced through the base so that its lower end constitutes one of the switch contacts. When a fuse plug is screwed into its socket it prevents the center stud from working loose.

A switch rotor 28 has a hub 29 and is rotatably mounted in the lower end of a tubular or hollow post 30. This rotor carries two contact buttons 31, 31. Each button is dropped into a hole 32 in the rocker and prevented from falling out by engagement of adjacent parts. The rocker is also provided with two shallow recesses 33, 33. The underside of the base is provided with an arcuate track 34 for guiding one of the contact buttons. This track is provided with transverse grooves 35 so as to interrupt the surface of the track and avoid the possibility of metal particles forming a conductor along the track. The free end of each of the spring arm contacts 22 is provided with a boss 36 in alignment with the adjacent contact stud 27. The rotor is provided with an inclined cam surface 37 at each end which extends between the recess 33 and the adjacent contact button 31. Each cam surface terminates in an abrupt shoulder 38 adjacent the contact button so that as the rotor is turned between the base and the bosses 36, 36 of the contact arms the contact arms will be placed under tension and then snapped on to the contact buttons thus indi-

cating clearly to the operator that the circuit has been closed. In breaking the circuit, the bosses 36, 36 drop into the recesses 33 and thus indicate that the switch has been turned to the fully "off" position.

The rotor is preferably provided with flanges 39, 39 which are interposed between the contacts and the operating shaft. The rotation of the rotor is limited by the opposite sides of an abutment 40. (Fig. 10.)

The switch is actuated by a shaft 41 which is preferably formed from a single stamping of sheet metal and has a handle 42. This shaft has a bearing washer 43 mounted on the upper end of the post 30 and the shaft has a limited longitudinal movement through the washer. The lower end of the shaft passes through a slot 44 in the rotor and is upset or spread at 45 to hold the parts together. A washer 46 is preferably provided to form a seat for the end of the shaft. The upper end of the shaft is provided with a washer 47 which has a boss which fits within an opening 48 in the cover. The washer is secured to the shaft and handle member by the lugs 49 which are integral with the upper end of the shaft. A spring 50 mounted on the shaft 41 is interposed between the lugs 49 and the washer 43 so as to exert a tension on the shaft and thus draw the rotor and its hub upward in the bottom of the post 30 when the box cover is open and also when the switch unit is removed from the box. The shaft has a shoulder 51 which coacts with the washer 43 to limit the downward movement of the shaft.

To provide a convenient means for locking the switch either in the "on" or "off" position, I have provided a lug 52 which may be integral with the cover and projects upwardly therefrom at the periphery of the opening 48. A latch 53 is pivoted at 54 to the handle member 42. This pivot is eccentric to the axis of the shaft so that the latch may be thrown into the full line position of Fig. 5 to limit the rotation of the handle and shaft or thrown into the dotted line position which prevents the latch from engaging the stop lug 52. The shaft handle may be provided with an opening 55 to accommodate a pad lock or other form of locking device (not shown).

The switch may be provided with a neutral terminal 56 and also provided with an insulating back plate 57 if desired.

The form of construction shown in Fig. 14 is designed to accommodate cartridge type fuses instead of the fuse plugs previously mentioned. For this purpose, fuse clips 60 and 61 are provided in place of the screw-threaded sockets previously mentioned. Otherwise the mechanism and operation is essentially the same as that previously described.

The construction thus shown and described provides a contact switch in which cable or wire connections may be made without interference with the switch operating mechanism. It leaves a clear wall space for cable entrance holes or knockouts in all four side walls of the box.

The spring construction on the handle shaft eliminates any loose feeling of the parts although they are slidably connected. The spring also pushes the flange on the handle washer 47 into a snug seal with the inside of the cover when the cover is closed. This prevents any accidental flash or fire through the handle hole in the cover should there be an explosion within the box.

The sliding connection of the handle shaft

also allows for manufacturing variations in the dimensions of the box and the switch mechanism. The movable contacts float or slide in the rotor and the handle shaft floats or slides in the rotor so that if the handle is depressed during cover closing or by accident, strain upon the resilient contacts will be minimized and connection of the circuit through the switch will not be interrupted.

10 Although I have shown the invention as applied to a 2-pole switch, it should be understood that various features are applicable to 3-pole and 4-pole switches.

15 The invention involving the switch and its relation to the housing is claimed in my application Serial Number 45,909 filed August 24, 1948.

I claim:

20 1. An electric switch having a base, an actuating shaft rotatably mounted in said base, a two-armed rotor mounted on the lower part of said shaft beneath said base, a contact loosely carried by each arm of said rotor, spring contact arms carried by said base, contacts mounted in the base in alinement with the ends of said arms, said base having tracks for said rotor contacts leading to the contacts in the base, said rotor having cam faces inclined toward its contacts and terminating in shoulders at the edges of the respective contacts for causing the spring contact arms to snap from said shoulders to engage the base contacts when the rotor is turned.

25 2. An electric switch having a base, an actuating shaft rotatably mounted in said base, a two-armed rotor mounted on the lower part of said shaft beneath said base, a contact loosely carried by each arm of said rotor, said rotor having a recess in each arm spaced circumferentially from its contact, spring contact arms carried by said base having terminal bosses, contacts mounted in the base in alinement with said bosses, said base having tracks for said rotor contacts leading to the contacts in the base, said rotor having shoulders at the edges of the respective contacts for causing the bosses of the spring contact arms to snap from said shoulders to engage the base contacts when the rotor is turned.

30 3. An electric switch having a base, an actuating shaft rotatably mounted in said base, a two-armed rotor mounted on the lower part of said shaft beneath said base, a contact loosely carried by each arm of said rotor, said rotor having a recess in each arm spaced circumferentially from its contact, spring contact arms carried by said base and having terminal bosses, contacts mounted in the base in alinement with said bosses, said base having tracks for said rotor contacts leading to the contacts in the base, said tracks having grooves transverse to the direction of movement of said rotor contacts, said rotor having cam faces leading from its recesses and inclined toward its contacts and terminating in shoulders at the edges of the respective contacts for causing the bosses of the spring contact arms to snap from said shoulders to engage the base contacts when the rotor is turned.

35 4. In a switch construction, a base having fuse plug center contact studs extending through the base from front to rear, a fuse socket surrounding each stud the rear ends of said studs constituting switch contacts, spring switch arms secured at one end of each to the base and each having a free end extending directly beneath a switch contact and a rotor supported in the base having 40 contact members and oscillated to bring said con-

tact members between the ends of the switch arms and the respective switch contacts and a shaft for actuating the rotor.

5. In a switch construction, a base having fuse plug center contact studs extending through the base from front to back, a fuse socket surrounding each stud the rear ends constituting switch contacts, switch arms secured at one end of each to the base and each having a free end extending directly beneath a switch contact and a rotor supported in the base having contact members and oscillated to bring said contact members between the ends of the switch arms and the respective switch contacts, said contact members being loosely slidable axially in the rotor and a shaft for oscillating the rotor.

6. In a switch construction, a base having fuse plug center contact studs extending through the base from front to back, a fuse socket surrounding each stud the rear ends constituting switch contacts, spring switch arms secured at one end of each to the base and each having a free end extending directly beneath a switch contact and a rotor supported in the base having contact members and oscillated to bring said contact members between the ends of the switch arms and the respective switch contacts and a spring-pressed shaft for actuating the rotor movable longitudinally of the base and of the rotor.

7. In an electric switch, an insulating base having a tubular post integral therewith and projecting upwardly from the central part of the base and having a recess in the lower face of the base, an insulating rotor mounted in said recess and having contact buttons with upper and lower exposed contact surfaces, line terminal members secured to the base, each terminal member consisting of a strip of metal with a spring contact arm at the rear of the base extending into said recess and having a contact end pressing against said rotor in an open circuit position and against one of the contact buttons when the circuit is closed, fuse receiving means mounted on the front of the base at a side opposite the line terminal members, each fuse receiving member having a contact at its rear in alignment with the spring-pressed contact end of one of the line terminal members, an actuating shaft extending through said post and connected at its inner end with said rotor, an abutment at the outer end of the shaft, and a spring on said shaft between said post and said abutment for pressing said rotor toward said base.

8. In an electric switch, an insulating base having a tubular post integral therewith and projecting upwardly from the central part of the base and having a recess in the lower face of the base, an insulating rotor mounted in said recess and having contact buttons with upper and lower exposed contact surfaces, line terminal members secured to opposite sides of the base, each terminal member consisting of a single strip of metal extending around an edge of the base with a binding screw at the front of the base and a spring contact arm at the rear of the base extending into said recess and having a contact end pressing against said rotor in an open circuit position and against one of the contact buttons when the circuit is closed, fuse receiving means mounted on the front of the base at a side opposite the binding screws of the line terminal members, each fuse receiving member having a contact at its rear in alignment with the spring-pressed contact end of one of the line terminal members and a binding screw at the front of the base, an actuating shaft extending through said post and connected at its inner end with said rotor, an abutment at the outer end of the shaft, and a spring on said shaft between said post and said abutment for pressing said rotor toward said base.
